R. C. RUSSELL

RADIATOR CAP

Filed Nov. 11, 1922

UNITED STATES PATENT OFFICE.

ROBERT C. RUSSELL, OF DALLAS, TEXAS, ASSIGNOR TO REES-RUSSELL MANUFACTURING COMPANY, OF DALLAS, TEXAS, A COPARTNERSHIP COMPRISED OF WILLIAM REES, ROBERT C. RUSSELL, AND EVAN REES.

RADIATOR CAP.

Application filed November 11, 1922. Serial No. 600,414.

To all whom it may concern:

Be it known that I, ROBERT C. RUSSELL, citizen of the United States, residing at Dallas, in the county of Dallas and State of Texas, have invented certain new and useful Improvements in Radiator Caps, of which the following is a specification.

This invention relates to new and useful improvements in radiator caps.

10 The object of the invention is to provide a radiator cap of the quick opening type and to include means for securing the cap on the radiator filling collar in such a manner that it cannot be removed without the aid of tools, thus defeating the usual attempts to steal the cap and any ornament or motor-meter it may support.

An important object of the invention is to provide a ring and sleeve combination 20 which will co-operate with the filling collar of a radiator in such a manner as to prevent either upward or downward displacement of the ring, while at the same time permitting rotation of said ring, unless the same is 25 fastened.

A further object of the invention is to provide a cap comprising two main members, one of which when screwed into the collar cannot be removed without the aid of the 30 other member, together with means for connecting the members together when it is desired to legitimately remove the cap. A still further object is to render the means of connection between the members more difficult 35 to effect, after the cap has once been placed in position.

Another object of the invention is to mount one of the members so that it may be 40 freely rotated without removing the cap and to mount on said member the ornamental arms, ornaments, motor-meter and quick opening filling lid together with its fastening means, whereby the said parts may be properly aligned with the front of the radiator or swing out of the way to permit removal of the hood.

One of the advantages of my invention is 45 that the cap may, with the aid of the proper tools, be removed from the filling collar without removing the radiator or other part of the car.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a plan view of a cap constructed 60 in accordance with my invention,

Fig. 2 is a front elevation of the same,

Fig. 3 is a rear elevation,

Fig. 4 is an enlarged vertical sectional view,

Fig. 5 is an enlarged sectional detail of 65 the plug receiving parts,

Fig. 6 is a detail of the plug,

Fig. 7 is an enlarged elevation of the sleeve, and

Fig. 8 is a sectional detail of the ring.

In the drawings the numeral 10 designates a cylindrical sleeve having its lower portion reduced and provided with external screw threads 11 above which the sleeve has an 75 overhanging annular shoulder 12 as is shown in Figs. 4 and 5. At its upper end the sleeve has an outwardly directed annular flange 13.

A ring 14 surrounds the upper portion of the sleeve and has its lower edge terminating flush with the shoulder 12. The ring projects above the sleeve, but is reamed out to form an annular shoulder 15 on which the flange seats. The flange has its upper surface flush with the upper edge of the sleeve, thus forming an annular seat 16 for a gasket 18 which surrounds an upstanding lip 17 on the inner edge of said sleeve.

A boss 19 is formed on the rear side of the ring and supports a pair of spaced ears 20 between which a hinge lug 21 is received. A pintle 22 passing thru the parts 20 and 21 hinges them together. The lid 23 has a general frusto-conical shape and is hollow. The lid has an annular apron 24 on its lower edge fitting in the upper side of the ring and bearing upon the gasket 18.

The ring is also provided with bosses 25 on each side of its front in which a transversely elongated bail 26 is pivoted. The lid has a lug 27 on its front over which the bail is adapted to engage and fastens the

apron down upon the gasket, whereby a water-tight joint is had. To open the lid it is merely necessary to swing the bail forwardly and swing the lid upwardly upon its hinge.

The lid has a central opening 28 normally closed by a compression plug 29, which may be of any approved construction and which is removed when it is desired to 19 mount a motor-meter or ornament on the lid. The ring is provided at right angles to the lugs 20 and 27 with integral balls 31 on their outer ends. However it is to be understood that the arms may be dispensed 25 with and any suitable fastening means for the lid may be used.

The sleeve is screwed into the flange 32 of a radiator filling collar 33 such as is common on automobile radiators. The upper 20 edge of the flange 32 receives the shoulder 12 of the sleeve and also the lower edge of the ring 14 and the latter is free to rotate thereon around the sleeve, being held against upward displacement by the flange 25 13 and shoulder 15. In order to connect the ring and sleeve as a unit a set screw 34 is threaded into an opening 35 in the boss 19 and engaged in a sump 36 in the sleeve. When so connected the ring will rotate the 30 sleeve, but when the screw is removed the ring will rotate without turning the sleeve. When the screw is removed the opening 35 is filled with a hollow plug 37 which is wedged therein, but does not engage the 35 sump.

It will be seen that when the sleeve is screwed into the flange 32 as far as it will be the arms 30 may extend at an angle to the front of the radiator. When the screw 40 34 is removed and the plug 37 inserted in the opening 35, the ring 14 and sleeve 10 are disconnected. The ring and arms may be thus freely rotated so that the arms are aligned with the front of the radiator or may 45 be turned to any position. Further one attempting to remove the cap could not turn the sleeve unless some connection between the ring and sleeve was made thru the opening 35.

When it is necessary to remove the cap a small hole is drilled in the end of the plug 37 and a hook inserted by which the plug may be pulled out. The ring is then rotated until the sump 36 is visible and a 55 screw is screwed into the opening 35 and engaged in the sump, whereby the ring and sleeve are connected and the sleeve may be unscrewed by rotating the ring. This is accomplished without removing the 60 radiator or disturbing any other part of the car. When it is desired to fill the radiator it is merely necessary to swing the bail 26 forwardly and raise the lid 23. After the filling operation the lid is swung 65 down and the bail swung upwardly and

sprung over the lug 27 whereby the gasket 18 is compressed by the apron 24 and a water-tight closure is had.

A structure of this nature permits of various changes in the size and shape of the 70 various parts and such changes together with modifications may be made within the scope of the appended claims.

What I claim is:

1. In a radiator cap, a sleeve adapted to 75 be attached to the filling collar of a radiator, a ring mounted to rotate on the sleeve, a filling lid and fastening therefor mounted on the ring, removable means for fastening the ring and sleeve together, and a plug for filling the opening left by the removable means.

2. In a radiator cap, a sleeve adapted to be attached to a radiator filling collar, a ring rotatably confined on the sleeve, a gasket carried by the sleeve within the ring, a lid hinged on the ring and engaging the gasket, means on the ring fastening the lid in its closed position, and a screw passing thru the ring and engaging in the sleeve for 90 connecting the ring and sleeve whereby the sleeve may be turned by the ring, the screw being removable whereby the ring is free to rotate.

3. In a radiator cap, a sleeve adapted to 95 be attached to a radiator filling collar, a ring rotatably confined on the sleeve, a gasket carried by the sleeve within the ring, a lid hinged on the ring and engaging the gasket, means on the ring fastening the lid 100 in its closed position, a screw passing thru the ring and engaging in the sleeve for connecting the ring and sleeve whereby the sleeve may be turned by the ring, the screw being removable whereby the ring is free 105 to rotate, and a plug for filling the opening in the ring left when the screw is removed.

4. In a radiator cap, a sleeve adapted to be attached to a radiator filling collar, a ring rotatably confined on the sleeve, a gasket carried by the sleeve within the ring, a lid hinged on the ring and engaging the gasket, means on the ring fastening the lid 110 in its closed position, a screw passing thru the ring and engaging in the sleeve for connecting the ring and sleeve whereby the sleeve may be turned by the ring, the screw being removable whereby the ring is free to rotate, and a hollow plug for filling 115 the opening left when the screw is removed and adapted to be removed by suitable tools to permit the reinsertion of the screw.

5. In a radiator cap, a sleeve having external screw threads at its lower end and a flange at its upper end, a ring rotatably surrounding the sleeve and having a shoulder receiving the flange, the screw threads of the sleeve projecting below the ring and adapted to engage in a radiator filling collar, the ring being located to rest on the 120 125 130

radiator filling collar, a gasket on the upper end of the sleeve, a lid hinged on the ring and engaging the gasket, the ring having a screw threaded opening, the sleeve having a sump located to register with the opening, a set screw filling in the opening of the ring and the sump of the sleeve, and a plug fill-

ing in the opening of the ring but free from the sump of the sleeve whereby the ring is free to rotate.

10

In testimony whereof I affix my signature.

ROBERT C. RUSSELL.
